UNITED STATES PATENT OFFICE.

HARRY V. G. DOHM, OF CHICAGO, ILLINOIS.

DESIGN FOR A COMBINATION LAMP AND SMOKER'S STAND.

Application filed July 14, 1923. Serial No. 6,779. Term of patent 3½ years.

To all whom it may concern:

Be it known that I, HARRY V. G. DOHM, a citizen of the United States, residing at Chicago, in the county of Cook and State of Illinois, have invented a new, original, and ornamental Design for a Combination Lamp and Smoker's Stand, of which the following is a specification, reference being had to the accompanying drawing, forming part thereof.

Figures 1 and 2 are front and side views respectively of a combination lamp and smoker's stand, showing my new design.

The design comprises a combination lamp and smoker's stand having a tray at the base with smoking outfit or receptacles for toilet articles and having a frame for a picture on the standard above the tray.

I claim:

The ornamental design for a combination lamp and smoker's stand, as shown and described.

HARRY V. G. DOHM.
